YARN CREEL AND OTHER APPARATUS

William Pool, Spondon, near Derby, England, assignor to Celanese Corporation of America, a corporation of Delaware

Application April 15, 1937, Serial No. 137,037
In Great Britain May 6, 1936

9 Claims. (Cl. 242—156)

This invention relates to textile machinery, and in particular to creels such as are used for the supply of warp mills or other apparatus where a single package is fed from a number of bobbins simultaneously. A creel according to the invention is arranged to accommodate flanged bobbins, spools, cheeses, cones, or other packages, and to provide for the unwinding of the threads by a rotation of the packages.

According to one feature of the invention bearings are provided for the upper and lower ends of spindles adapted to receive the packages so as to enable these to rotate about a vertical axis. Since both ends of the package spindles are supported, very free rotation is afforded, which enables the thread under the pull of the warping mill or other device to rotate the package easily and without danger of excessive tension being developed. The ends of the spindles are preferably formed as hardened conical points adapted to engage suitably shaped cups for free rotation.

A further feature of the invention consists in mounting one or both of the cups in a spring holder to enable the spindle carrying the package to be snapped into position, and there held for free rotation about the vertical axis. Guide means may be provided in connection with one or both cups to permit the spindle to be readily slipped into position.

Another feature of the invention comprises a thread guide arranged for free vertical movement just clear of the periphery of the package, the thread being led from the package through the guide to a position over the package, so that during unwinding the guide is caused to traverse up and down and lead the thread smoothly from the package, an arrangement that is of special advantage when the package is flanged. In cases where two or more threads are wound together upon a single bobbin a sliding guide may conveniently be provided for each thread to facilitate the separation of the threads during the unwinding and prevent entanglement.

A further feature of the invention comprises means for rapidly stopping the rotation of the package whenever the pull of the thread ceases, for instance when winding stops or when the thread breaks. Thus, over-running of the package and the consequent entanglement of the thread are avoided. Conveniently the thread-supported guide is used for this purpose, there being provided a projection rotating with the package into the path of which the guide falls when the thread becomes slack or breaks. For instance, the projection may be formed on a base

portion of the spindle on which the package sits; thus two or more such projections may be formed round the periphery of the base so that one of these engages the guide (or a projection from the guide) after a very small rotation of the package following the fall of the guide.

The package may fit relatively freely on the spindle, a friction washer of felt or like material being interposed between the lower end of the package and the base of the spindle so as to enable the spindle to be driven by the rotation of the package. When the base of the spindle is prevented from rotating as described above, the package can continue its rotation only until its kinetic energy is dissipated by the friction between the package and the washer, so that the package is brought to rest after a slight over-run.

The invention will now be described with greater detail with reference to the accompanying drawing and in connection with a creel suitable for the accommodation of a large number of flanged bobbins such as is necessary for the formation of a beam section or the building up of a warp on a warping mill.

In the drawing:

Fig. 1 is an elevation of a part of the creel;

Fig. 2 is a side elevation of part of Fig. 1;

Fig. 3 is an enlarged partial elevation of Fig. 1 showing the lower spindle bearing and guide member;

Fig. 4 is an enlarged part plan view of Fig. 1, showing two guides for a single bobbin;

Fig. 5 is a part plan view of a creel showing a number of bobbin mountings;

Fig. 6 is a part plan view showing an arrangement of a number of creels supplying a common warping mill.

The creel framework consists of a pair of vertical channel irons 1 connected by a series of light channel irons 2 disposed at a vertical distance apart somewhat in excess of the over-all length of the bobbins to be accommodated. Flat strips 3 are secured by means of rivets 4 to the lower flanges of the channels 2 at intervals along the length of the latter. The strips 3 project horizontally to each side of the channel 2 to form extensions 5 and 6, the extension 6 projecting a greater distance than the projection 5. Each successive strip 3 throughout the length of the creel has its longer projection 6 on the opposite side of the channel 2 to the previous strip. Further flat strips 7 are secured by rivets 8 to the upper flanges of the channels 2 at intervals along the length of the latter and project an equal distance to each side of the channels 2, the distance being 55

equal to the projections 5 of the strips 3. The strips 3 of an upper channel 2 and the strips 7 of a lower channel provide support for bearing cups 9 in which the spindles 10 rotate, one bearing cup 9 being secured to the shorter projecting portion 5 of the strip 3 and the other bearing cup 9 being secured to the portion of the strip 7 immediately below the portion 5. The portion 5 of the strip 3 is formed of springy material, to allow the spindle to snap into position. Guide plates 11 are secured to the projecting portions of the strips 3 and 7 on the appropriate side of the channel 2 to facilitate the insertion of the spindles and to ensure that the spindles are properly engaged by the bearing cups.

The diameter of the spindles 10 is slightly less than the diameter of the bore of the bobbins so that the spindles enter the bores of the bobbins quite freely. The spindles 10 are provided at each end with hardened steel cone points 12 which engage with the bearing cups 9. Each spindle 10 is provided with a base 13 substantially the same in diameter as the bobbin flange and a friction washer 14 of felt or like material is interposed between the bobbin and the base 13.

The portions 6 of the strips 3 and the portions of the strips 7 immediately below the portions 6 are connected by a pair of vertical rods 15 and 16 lying just clear of the bobbin periphery. A thread guide 17, in the form of a porcelain hook, is carried by a support 18, which is formed from a length of wire which is first twisted round the stem of the hook 17 leaving two ends, one of which passes round one side of the rod 15 and the other round the other side. The two ends are then twisted into two loops 19 and 20 round the rod 16. The whole support 18 carrying the guide 17 is thus free to move up and down the rod 16 while at the same time being prevented from rotating about this rod by its engagement with the rod 15.

The part of the wire support 18 which connects the two loops 19 and 20 is bent outwardly from the rod 16 and towards the centre of the spindle to form a projection 21 long enough to come into the path of a pair of projections 22 formed on the base 13 of the spindle.

The longer projecting portions 6 of the strips 3 at a point vertically above the guide 17 are punched out to form tongues 23 which provide a support for a horizontal porcelain guide 24. The thread A from a bobbin is passed through the hook of the guide 17 and upwards over or round the horizontal guide 24 to one of a series of eyes 25 formed in a horizontal projecting plate 26 carried by the vertical channel iron 1 at one end of the creel. The various guides may with advantage be made from unglazed porcelain when low twist continuous filament threads are being handled.

The guide 17 is traversed up and down the rods 15 and 16 during the course of unwinding of the thread A from the bobbin, so that if the pull of the thread ceases, for instance when winding stops or when the thread breaks, especially at a point remote from the bobbin, the guide 17 falls to the bottom of the rods 15 and 16. When the guide 17 is in this position the projections 22 on the base 13 cannot pass the projection 21 on the guide support 18 and the spindle is prevented from rotating. When bobbins are used which have two or more threads wound together, two or more hooks 17 are provided, as shown in Fig. 4, one for each thread B and C, the guide

supports 18 and the vertical rods 15 and 16 being likewise duplicated.

The friction washer 14 is made of felt or like material and allows the spindle 10 to be frictionally driven by the rotation of the package. When the spindle is prevented from rotating, as described above, the frictional resistance of the washer 14 acts as a brake on the base of the package, which is rapidly brought to rest.

From the horizontal guide 24 to the eye 25 in 10 the end plate 26 the thread passes horizontally at a height above the bobbin so that all the threads lie clear of the bobbins and permit any bobbin to be readily removed from, or replaced in, the bearing cups 9. The extensions 6 of the 15 horizontal strips 3 support the threads when they become slack and a lip 27 is formed on the end of the extension 6 to prevent the threads slipping off the strips.

The staggered arrangement of the strips 3 20 allows half the bobbins to deliver their threads to one side of the creel and the other half to the other side. As many rows of bobbins are arranged horizontally one above the other as can conveniently be reached by the operative and 25 the length of the creel between the vertical channel 1 is such as to enable the total desired number of bobbins to be accommodated. An eye 25 is provided for each thread and they are arranged in banks in the projecting members 26, there 30 being one blank for each row of bobbins. A plurality of creels can be disposed side by side, as shown in Fig. 6, in accordance with the total number of threads that are simultaneously beamed, sufficient space being left between the 35 creels 28 to enable the operative to reach the bobbins. Preferably, the assembly of creels is disposed so as to taper slightly towards the warping mill 29 so as to enable all the threads from each creel to pass smoothly to the reed 30 of 40 the mill.

Having described my invention, what I desire to secure by Letters Patent is:—

1. A mounting for a bobbin or like package comprising a vertical spindle adapted to receive the package, bearings adapted to receive the ends of said spindle, a member rotatable with said spindle, a thread guide, and carrying means adapted to permit said guide to be traversed lengthwise of the package by the thread during unwinding, said guide being adapted to move, when the thread fails to support it, into contact with said member, thereby stopping the rotation of said member and the package.

2. A mounting for a bobbin or like package comprising a vertical spindle, a base on said spindle adapted to receive the package, bearings adapted to receive the ends of said spindle, a friction washer between the package and said base, through which washer said spindle is frictionally 60 driven by the package, a member rotatable with said spindle, a thread guide, and carrying means adapted to permit said guide to be traversed lengthwise of the package by the thread during unwinding, said guide being adapted to move, when the thread fails to support it, into contact with said member, thereby stopping the rotation of the spindle and, by the frictional resistance of said washer, the package.

3. A mounting for a bobbin or like package comprising a vertical spindle adapted to receive the package, bearings adapted to receive the ends of said spindle, a member rotatable with said spindle, a number of thread guides to enable a corresponding number of threads to be unwound 75

from a single package, and carrying means adapted to permit each of said guides to be traversed lengthwise of the package by its thread during unwinding and, upon failure of any 5 thread, to allow the corresponding thread guide to move into contact with said member, thereby stopping the rotation of said member and the package.

4. A mounting for a bobbin or like package 10 comprising a vertical spindle adapted to receive the package, bearings adapted to receive the ends of said spindle, a base on said spindle adapted to support the package, a projection on said base, a thread guide, and carrying means adapted to 15 permit said guide to be traversed lengthwise of the package by the thread during unwinding, said guide being adapted to fall, when the thread fails to support it, into the path of said projection, thereby stopping the rotation of the spindle 20 and, by the increased frictional resistance resulting, the package.

5. A mounting for a bobbin or like package comprising a vertical spindle adapted to receive the package, bearings adapted to receive the 25 ends of said spindle, a base on said spindle adapted to support the package, a projection on said base, a friction washer between said package and said base through which washer said spindle is frictionally driven by said package, a thread 30 guide, and carrying means adapted to permit said guide to be traversed lengthwise of the package by the thread during unwinding, said guide being adapted to fall, when the thread fails to support it, into the path of said projection, thereby stopping the rotation of the 35 spindle and, by the frictional resistance of said washer, the package.

6. A mounting for a bobbin or like package comprising a vertical spindle adapted to receive the 40 package, bearings adapted to receive the ends of said spindle, a base on said spindle adapted to support the package, a projection on said base, two vertical rods, means to support said rods and a thread guide freely mounted

on said rods and supported by the thread, said guide being adapted to fall, when the thread fails to support it, into the path of said projection, thereby stopping the rotation of the spindle and, by the increased frictional resistance 5 resulting, the package.

7. A creel or other package supporting device 10 comprising a plurality of vertical spindles adapted to support the packages, bearings adapted to receive the ends of each of said spindles, a member rotatable with each of said spindles, a thread guide for each of said spindles, and carrying means adapted to permit the guides to be traversed lengthwise of the packages by their threads during unwinding, each guide being adapted to 15 move, when its thread fails to support it, into contact with the corresponding rotatable member, thereby stopping the rotation of said member and the package.

8. A creel according to claim 7 wherein the 20 member rotatable with each of said spindles is formed with a projection into the path of which the corresponding thread guide is adapted to move.

9. A creel or other package supporting device 25 comprising a frame, a series of horizontal members connected to said frame, a plurality of bearing carrying members connected to and disposed at right angles to said horizontal members, a plurality of vertical spindles disposed between said bearing carrying members and adapted 30 to support the packages, bearings carried by said bearing carrying members and adapted to receive the ends of said spindles, a member rotatable with each of said spindles, a thread 35 guide for each of said spindles, and carrying means adapted to permit the guides to be traversed lengthwise of their packages by their threads during unwinding, each guide being adapted to move, when its thread fails to support 40 it, into contact with the corresponding rotatable member, thereby stopping the rotation of said member and the package.
